UNITED STATES PATENT OFFICE.

GEORGE T. RONK, OF FAIRFIELD, IOWA.

HOISTING MECHANISM.

Application filed February 24, 1925. Serial No. 11,305.

The object of my invention is to provide an improved hoisting mechanism of simple, durable and inexpensive construction.

A further object is to provide in a hoisting mechanism, including a rotary cable drum, a single lever for controlling said drum to throw it into operation with the driving mechanism for winding it to release it to permit the cable to unwind, and provided with means whereby the drum will be automatically locked against rotation upon releasing said lever.

My invention consists in the construction, arrangement and combination of the various parts of the device, whereby the objects contemplated are attained, as hereinafter more fully set forth, pointed out in my claims, and illustrated in the accompanying drawings, in which:

20 Figure 1 is a plan view of my improved hoisting mechanism.

Figure 2 is a sectional view taken on the line 2—2 of Figure 1.

25 Figure 3 is a detail sectional view taken on the line 3—3 of Figure 1.

Figure 4 is a detail sectional view taken on the line 4—4 of Figure 2.

Figure 5 is a detail view of one of the band controlling devices.

30 My improved device comprises a base 10 formed of a pair of parallel beams 11. Mounted on the beams 11 are transversely arranged beams 12 designed to carry the beams 13 which extend above and parallel 35 with the beams 11 and which are designed to support my improved mechanism.

35 Mounted on top of two of the beams 11 and transversely therewith is a driving shaft 14 carrying a belt pulley 15, the inner end 40 of the shaft being provided with a pinion 16 designed to mesh with a spur gear 17 mounted on the inner end of a driven shaft 18. The shaft 18 is mounted between suitable 45 bearings 19 and designed to carry the cable drum 20 rotatively mounted on said shaft.

One end of the drum 20 is provided with a brake drum 21, while the other end is provided with what I shall term a driving drum 22. The drum 21 is provided with a brake band 23, one end of which is rigidly connected to a pin 24, while the other end is connected to a draw bar 25. The free end of the draw bar 25 is pivotally connected to an arm 26 rigidly secured to a rock shaft 27. Adjacent to the driving drum 22

is a driving arm 28 rigidly secured to the shaft 18, one end of which is provided with an inwardly extending pin 29 designed to carry one end of a driving band 30 which extends around the said drum 22, and has its opposite end pivotally connected to a lever 31. The said lever 31 is pivotally connected to the arm 28 by means of the bolt 32. The said arm 31 extends with its inner end substantially adjacent to the shaft 18 when the band 30 is in a released position. The outer end of the shaft 18 is provided with a sliding cone 33 having an annular groove 34 designed to receive pins 35 of the operating lever 36. One end of the lever 36 is pivoted at 37 to a bracket 38. The other end of the lever 36 is pivotally connected to a bell crank lever 39, said lever being pivoted to a bracket 40. The bell crank lever 39 is actuated by means of a link 41 pivotally connected to a downwardly extended arm 42 secured to the shaft 27. The inner end of the shaft 27 is provided with an upwardly and rearwardly extended arm 43, the upper end of which is connected to one end of a contractile coil spring 44. The other end of the spring 44 is secured to a bracket 45 mounted on the top edge of one of the beams 11. The arm 43 is pivotally connected to a link 46, the free end of which is adjustably connected with a hand lever 47 mounted on a rock shaft 48, which is in turn pivotally mounted in the beams 11. The rock shaft 48 is provided with a foot lever 49 having its free end provided with a treadle 50.

The drum 20 is provided with a cable 51 which may be led to any desired position, it being illustrated as extended over a pulley 52 having at its lower end a weight 53.

The practical operation of my device is as follows:

Assuming that power is applied to the pulley 15 through the belt 54, and the shaft 14 is being rotated, causing the shaft 18 to be continuously rotated through the gears 16 and 17, it will be seen, through the construction of the device, that the brake band 23 will be retained on the drum 21 through the action of the spring 44, said spring causing the upper end of the arm 43 to be moved downwardly and rearwardly, causing the upper end of the arm 26 to be moved rearwardly and the bar 25 to be moved upwardly. The parts are so arranged that when the band 23 is taut, the lower end of

the arm 42 will be moved forwardly, which will cause the rear end of the lever 36 to be moved outwardly from the drum, causing the cone 33 to be slid outwardly and out 5 of engagement with the lever 31, which will cause the band 30 to lie loosely over the driving drum 22. The weight 53 will then be suspended by the band 23.

If it is desired to lower the weight 53, 10 the operator grasps the upper end of the handle 47, or places his foot on the treadle 50, and moves the upper end of said handle forwardly slightly releasing the band 23, which will permit the weight 53 to descend 15 the desired distance, at which time the handle 47 may be released and the weight again retained in a new position.

If it is desired to elevate the weight 53, the upper end of the handle 47 is moved 20 forwardly to a greater extent, slightly releasing the band 23 and at the same time moving the lever 36 inwardly, the cone 33 into engagement with the lever 31 and the band 30 into engagement with the drum 22. 25 The arm 28 and the lever 31 being rotated continuously by the shaft 18 will cause the drum 20 to be rotated and the weight 53 elevated.

The parts are so adjusted that as the band 30 23 is being disengaged, the band 30 will be brought into engagement with the drum 22. It will be seen that when the lever 47 is moved to a certain position forwardly, both 35 of the bands will be partially released from their respective drums, which will permit the weight 53 to lower; but if the lever 47 is moved quickly past this point, the band 30 will engage its respective drum before any appreciable lowering of the weight 53 takes 40 place.

The cone 33 is moved into engagement with the lever 31 to cause the said lever to be swung about the pivot 32, and the band 30 to be drawn taut on the drum 22, causing 45 the drum 20 to be rotated and the weight elevated. The arm 26 is formed considerably longer than the arm 42, so that the brake band 21 may be quickly applied, while the brake band 22 will be more gradually 50 applied so that the said brake band may serve the purpose of a clutch, permitting a certain amount of slippage between the member 20 and the drum 22, while the weight is being started to elevate.

55 Thus it will be seen I have provided a hoisting mechanism of comparatively simple construction, which is very sensitive in its operation, and which may be controlled by a single lever, so that by releasing the 60 lever, the weight will be automatically suspended, which provides means whereby, if several levers are to be operated by a single operator, such as often happens in excavating machines for which this device is particularly adapted, the operator will not drop 65

the weight on account of becoming confused, which sometimes happens when new operators are being trained.

I claim as my invention:

1. In combination, a supporting frame, a 70 drum shaft, a cable drum rotatively mounted on said shaft, said drum having at one end a brake drum and at its opposite end a driving drum, a driving arm secured to said drum shaft, a lever pivoted to said arm, an 75 external clutch band for said driving drum having one end connected to said driving arm and its other end connected to one end of said pivoted lever, the free end of said lever extending inwardly adjacent to said driving shaft, a conical sleeve slidably mounted on said shaft and designed to engage said pivoted arm to tighten said brake band, an 80 external brake band for said brake drum, a rock shaft, a control lever, means for imparting movement from said control lever to said rock shaft, means for operatively connecting said rock shaft with said conical sleeve, means for operatively connecting said rock shaft with the brake band of said brake drum, the parts being so arranged that when 85 the rock shaft is in one position of its movement the brake band will be drawn taut and the conical sleeve released, and when in another position of its movement the brake band of said brake drum will be released and the conical sleeve moved into contact with said pivoted arm for locking said driving drum and said driving shaft in unison, and a spring for applying yieldable pressure to said brake band. 90

2. In combination, a supporting frame, a driving shaft, a driven shaft, means for imparting movement from said driving shaft to said driven shaft, a cable drum rotatably mounted on said driven shaft, said cable drum having at one end a brake drum and at its opposite end a driving drum, a driving arm secured to said driven shaft, a lever pivoted to said arm, a band for said driving drum having one end connected to said driving arm and its other end connected to one end of said pivoted lever, the other end of said lever extending inwardly adjacent to said driven shaft, a conical sleeve slidably mounted on said shaft and designed to engage said pivoted arm, a brake band for said brake drum, a control lever, means for operatively connecting said control lever to the said brake band and to the said sliding cone in such a manner that as the said lever is moved to one position of its movement the said brake band will be drawn taut, means for yieldably supporting said lever in said position, the parts being so arranged that when said lever is moved to another position of its movement, the brake band will be released and said cone thrown into engagement with said pivoted lever against the action of said yieldable means. 105

3. In combination, a supporting frame, a driving shaft, a driven shaft, means for imparting movement from said driving shaft to said driven shaft, a cable drum rotatably mounted on said driven shaft, said cable drum having at one end a brake drum and at its opposite end a driving drum, a driving arm secured to said driven shaft, a band for said driving drum having one end connected to said driving arm and its other end connected to a lever pivotally mounted on said driving arm, said lever having an inwardly extending arm adjacent to said driven shaft, a conical sleeve slidably mounted on said shaft and designed to engage said pivoted arm, a lever for imparting sliding movement to said conical sleeve, a bell crank lever for imparting movement to the last said lever, a rock shaft having down-

wardly extending arm, a link for operatively connecting said arm and said bell crank lever, said rock shaft also being provided with an upwardly extending arm, a brake band for said brake drum, one end of said band being fixed to said frame, a draw bar for connecting said upwardly extending arm with one end of said brake band, a spring having one end connected to said frame and its other end operatively connected with the said rock shaft to impart rotary movement thereto to draw said brake band taut, a lever, means for connecting said lever to said rock shaft to release said brake against the action of said spring and tighten the band of said driving drum. 35

Des Moines, Iowa, October 8, 1924.

GEORGE T. RONK.
